PARTITIONED BOTTLE CARRIER

Joseph Kramer, Reading, Ohio, assignor to The Gardner Board and Carton Co., Middletown, Ohio, a corporation of Ohio

Application August 30, 1952, Serial No. 307,249

3 Claims. (Cl. 220—113)

My invention relates to receptacles or containers for the packaging and transportation of bottles and like articles wherein a plurality of such articles may be conveniently carried as a group.

It is a principal object of my invention to provide a carrier which may be manufactured from paperboard or similar inexpensive material and fabricated from a single blank of such material, the carrier being of knock-down character so that it may be shipped to the user in substantially flat condition and set up for use without requiring special equipment or additional fastening means, and when so set up will constitute an effective packaging and carrying receptacle for a plurality of bottles or the like.

It is a further object of my invention to provide a collapsible bottle carrier which, upon being properly set up, will remain in the set up condition even though empty, thus facilitating the insertion of the bottles or other articles into it.

Yet another object of my invention is the provision of a partitioned carrier structure in which the interior thereof is divided into a plurality of rows by means of a central longitudinal partition and handle forming part, and the rows in turn divided into individual cells or compartments by means of transverse partition elements extending between the central longitudinal partition element and the side walls of the carrier.

Yet another object of my invention is the provision of a readily collapsible carrier structure in which the transverse partition elements are automatically erected and collapsed together with the body walls of the carrier, and in which the transverse partition elements are formed integrally with the carrier side walls.

These and other objects of my invention which will appear hereinafter, or which will be apparent to the skilled worker in the art upon reading the description which follows, I accomplish by that construction and arrangement of parts of which I shall now describe an exemplary embodiment.

Reference is now made to the accompanying drawings wherein:

Figure 1 is a plan view of the cut and scored blank for my carrier.

Figure 2 is a plan view similar to Figure 1 with certain of the parts infolded.

Figure 3 is a sectional view taken along the line 3—3 of Figure 2.

Figure 4 is a plan view of the blank in an intermediate stage of folding.

Figure 5 is a plan view of the blank in substantially completely folded condition.

Figure 6 is a fragmentary plan view illustrating the final folding step to complete the formation of the blank into a knocked-down carrier structure.

Figure 7 is a sectional view taken along the line 7—7 of Figure 5 with the parts in slightly expanded condition.

Figure 8 is a sectional view similar to Figure 7 illustrating the carrier in the fully erected condition.

2

Figure 9 is a perspective view of the erected carrier with parts broken away.

Figure 10 is an end elevation of the fully erected carrier structure.

5 Figure 11 is a plan view of a modified blank for my carrier.

Figure 12 is a partial plan view of the blank of Figure 11 with certain of the parts infolded.

10 Figure 13 is an end elevation of the carrier formed from the blank of Figure 11.

Figure 14 is a partial side elevation of the carrier illustrated in Figure 13.

15 Figure 15 is a sectional view taken along the line 15—15 of Figure 14.

15 Figure 16 is a sectional view taken along the line 16—16 of Figure 14.

20 Referring now to Figure 1, there is illustrated a blank 1 cut from a sheet of paperboard having the required qualities of strength, flexibility and stiffness, the blank being cut and scored to provide a central partition and handle forming panel 2 having a hand hole opening 3 therein. A partial end wall panel 4 is articulated to a side edge of the center partition and handle forming panel 2 along score line 5, and a side wall panel 6 is articulated to the opposite side edge of said partial end wall panel 4 along the score line 7.

25 Partial end wall panels 8 and 9 separated by score line 10 are connected to the opposite side edge of side wall panel 6 along the score line 11, and a second side wall panel 12 is connected to the side edge of partial end wall panel 9 along score line 13. A partial end wall panel 14 is articulated to the opposite side edge of the side wall panel 13 along score line 15, and an elongated glue flap 16 extends freely beyond the opposite side edge of partial end wall panel 14 and is articulated thereto along the score line 17. A glue flap 18 is also provided on the free side edge of central partition forming panel 2, in the manner illustrated, and articulated to central partition and handle forming panel 2 along score line 19.

30 40 Bottom forming portions 20 and 21 are articulated to the bottom edges of side wall panels 6 and 12 respectively, and a glue flap 22 is articulated to the free side edge of bottom forming portion 20 along score line 23. A notch or recess 24 is formed between the bottom forming portion 20 and glue flap 22 adjacent the end edge of score line 23, the said notch being adapted, in the erected carrier, to receive the tongue 25 cut in the bottom edge of central partition forming panel 2. A mating tongue 26 is provided along the bottom edge of glue flap 16, and if necessary the bottom forming portion 21 may be recessed at 27 so as to coincide with the recess 24 between bottom forming portion 20 and glue flap 22.

35 45 The side wall panels 6 and 12 terminate upwardly in centrally disposed neck portions 28 and 29, respectively. A transverse partition element 30 is articulated to one side edge of neck 28 along score line 31, and an attachment flap 32 is formed as a prolongation of transverse partition element 30 and connected thereto along score line 33. The transverse partition element 30 and attachment flap 31 are separated from side wall panel 6 and partial end wall panel 4 by a line of cut 34. Similarly, a transverse partition element 35 is connected to neck 29 along score line 36, and attachment flap 37 is connected to the opposite end of transverse partition element 35 along score line 38; and the partition element and the attachment flap are separated from side wall panel 12 and partial end wall panel 14 by means of the line of cut 39. Additional transverse partition elements 40 and 41 are connected to the opposite side edges of the neck portions 28 and 29 along the score lines 42 and 43, respectively, and handle forming parts 44 and 45 are connected to the opposite edges of the transverse partition

elements 40 and 41 along score lines 46 and 47, respectively. The handle forming parts 44 and 45 are connected to each other along score line 48 which, it will be noted, constitutes a prolongation of the score line 10. The transverse partition elements 40 and 41 and the handle forming parts 44 and 45 are separated from the side wall panels and the partial end wall panels 8 and 9 by means of the line of cut 49, and the handle forming parts are additionally separated from the neck portions 28 and 29 and the transverse partition elements 40 and 41 by means of the lines of cut 50 and 51. Hand hole openings 52 and 53, adapted to mate with the hand hole opening 3 in the center partition forming panel, are also provided in the handle forming parts 44 and 45.

The blank just described is assembled into a knocked-down carrier structure by first infolding the transverse partition elements 30 and 35 along the score lines 31 and 36, respectively, to the position illustrated in Figure 2 of the drawings. This also results in the infolding of the attachment flaps 32 and 37, as will be clearly apparent in both Figures 2 and 3. Next the blank is folded along the score line 7 to bring the center partition forming panel 2 into overlapping relation with the side wall panel 6 and partial end wall panel 8, with the handle forming part 2 juxtaposed on handle forming part 44, as illustrated in Figure 4 of the drawings. Prior to the folding of the blank along score line 7, adhesive is first applied to the attachment flap 32, handle forming part 44, and glue flap 18, as indicated by the shaded areas in Figure 2, so as to bring about the adhesive engagement of the handle forming part 44 and attachment flap 32 to central partition forming panel 2 and glue flap 18 to partial end wall panel 8. Alternatively, the adhesive may be applied to center partition forming panel 2, if so desired.

Either simultaneously with the infolding of the blank along the score line 7, or in sequence therewith, the blank is also infolded along the score line 15 so as to bring the upper portion of glue flap 16 into overlying contact with handle forming part 45, adhesive being first applied to the upper portion of glue flap 16, as indicated by the shaded area in Figure 2 of the drawings.

Following infolding of the blank along the score lines 7 and 15, the blank is next infolded along the coinciding score lines 10 and 19, and the score line 48, which is a prolongation of score line 10, thus bringing the blank to the condition illustrated in Figure 5. Prior to this folding step, adhesive is first applied to the blank in the manner illustrated by the shaded areas in Figure 4, so that in the folded condition the handle forming part 45, glue flap 16 and attachment flap 37 will be adhesively secured to central partition forming panel 2. As before, the adhesive may alternatively be applied to the center partition forming panel 2 rather than to the parts contacted thereby.

The final folding operation to complete the formation of the knocked-down carrier structure is illustrated in Figure 6, wherein adhesive is applied to the glue flap 22, as illustrated by the shaded area in Figure 5, whereupon the flap is then infolded to bring it into adhesive engagement with bottom forming portion 21.

As will be evident from Figures 7 and 8, the transverse partition elements lie parallel to the partial end wall panels, and the knocked-down carrier structure can be erected simply by applying inwardly directed pressure against the opposite ends of the carrier, which results in the squaring up of the side and end walls and the automatic extension of the transverse partition elements to the erected condition. As best seen in Figure 9, the carrier is maintained in erected condition by means of the mating tongues 25 and 26 which engage in the recess 24 intermediate an end edge of the bottom forming portion. The erected condition of the carrier may thus be maintained in spite of the resiliency of the board and prior to the loading of the carrier.

It will be apparent from the foregoing description that the folding and gluing of the carrier is such that the various steps may be conducted upon a high-speed, straight line gluer, as known in the art; and the folding and gluing operations hereinbefore described may also be performed on the right-angle type or other known types of folding and gluing equipment wherein means are provided to initially infold the transverse partition elements.

It will also be evident that my construction provides a fully partitioned, easily erected carrier which is of sturdy construction and yet economical to manufacture in that it requires a minimum amount of paperboard. The construction provides accurate cell definition which is essential where automatic loading and unloading equipment is employed, and the partitioning means are such that they will in no way interfere with the loading and unloading operations.

In Figure 11, I have illustrated a modification of the blank of Figure 1 wherein handle reinforcing portions 52 and 53 are articulated to the free end edges of handle forming parts 44 and 45. It will be noted that the handle reinforcing portions occupy areas of the blank which would otherwise be scraped out and thrown away, and hence the additional reinforcement of the handle is accomplished without any increase whatever in the amount of board used to form the carrier.

It will also be noted that the handle reinforcing portions 52 and 53 extend downwardly adjacent the ends of lateral partition elements 30 and 35 and the lateral partition elements are articulated directly to the handle reinforcing portion along the score lines 54 and 55, respectively. Thus, as can be best seen in Figure 12 of the drawings, when the handle reinforcing portions 52 and 53 are infolded to overlie handle forming parts 44 and 45, the transverse partition elements 30 and 35 are infolded together with the handle reinforcing portions. It will be understood that adhesive, indicated by the shaded areas in Figure 11 of the drawings, is applied to the handle reinforcing portions prior to the infolding thereof.

It will also be evident from Figure 11 of the drawings that the partial end wall panels 4 and 14, which lie beneath the lower extremities of the handle reinforcing portions, may now be provided with slanting upper edges which effectively increase the height of the end wall panels and thereby afford greater protection to the contents of the carrier. In the same manner, partial end wall panels 8 and 9 may be provided with slanting upper edges, as illustrated, and preferably the lines of cut 56 and 57, which define the top edges of the partial end wall panels, stop short of the line of articulation 10 connecting the partial end wall panels, thus providing a narrow neck indicated at 58. This is of particular advantage in assembling the carriers.

Once the handle reinforcing portions 52 and 53 have been infolded to the condition illustrated in Figure 12 of the drawings, the folding and gluing of the structure proceeds in the same manner as described in connection with the blank of Figure 1. For additional reinforcement, a glue flap 18a may be provided on the end of handle forming panel 2 above glue flap 18.

As will be evident from Figures 15 and 16, the construction just described provides an exceedingly strong handle construction and also provides for greater protection of the bottles at the ends of the carrier.

Modifications may be made in my invention without departing from the spirit of it. Having described my invention in an exemplary embodiment, what I desire to protect and secure by Letters Patent is:

1. In a blank for a partitioned bottle carrier construction, a side wall, a medially scored end wall, and a side wall in articulation in the order named; said side walls terminating upwardly in centrally disposed neck portions, adjoining handle forming parts extending above said side walls and said end wall, said handle forming parts being articulated together at their adjoining edges along a line

of articulation constituting a prolongation of the medial score line in said end wall, transverse partition elements integrally connecting said neck portions and said handle forming parts, said transverse partition elements being horizontally disposed and connected to said handle forming parts along lines of articulation constituting prolongations of the lines of articulation between said side wall panels and said end wall panel.

2. In a blank for a partitioned bottle carrier construction, a side wall, a medially scored end wall, and a side wall in articulation in the order named, said side walls terminating upwardly in centrally disposed neck portions, adjoining handle forming parts extending above said side walls and said end wall, said handle forming parts being articulated together at their adjoining edges along a line of articulation constituting a prolongation of the medial score line in said end wall, transverse partition elements integrally connecting said neck portions and said handle forming parts, said transverse partition elements being horizontally disposed and connected to said handle forming parts along lines of articulation constituting prolongations of the lines of articulation between said side wall panels and said end wall panel, partial end wall panels articulated to the opposite side edges of said side wall panels, and additional transverse partition elements extending outwardly from the remaining side edges of said neck portions, said additional transverse partition elements having attachment flaps articulated thereto and overlying said partial end wall panels, said attachment flaps being articulated to said additional transverse partition elements along lines of articulation constituting prolongations of the lines of articulation connecting said partial end wall panel to said side wall panels.

3. In a blank for a partitioned bottle carrier construction, a side wall, a medially scored end wall, and a side wall in articulation in the order named, said side walls terminating upwardly in centrally disposed neck portions, adjoining handle forming parts extending above said side wall and said end wall, said handle forming parts being articulated together at their adjoining edges along a line of articulation constituting a prolongation of the medial score line in said end wall, transverse partition elements integrally connecting said neck portions and said handle forming parts, said transverse partition elements being horizontally disposed and connected to said handle forming parts along lines of articulation constituting prolongations of the lines of articulation between said side wall panels and said end wall panel, partial end wall panels articulated to the opposite sides edges of said side wall panels, additional transverse partition elements extending outwardly from the remaining side edges of said neck portion, and handle reinforcing portions articulated to the opposite side edges of said handle forming parts, said additional transverse partition elements being articulated to said handle reinforcing parts along lines of articulation constituting prolongations of the lines of articulation between said partial end wall panels and said side walls.
